KNITTED FABRIC

Guido O. Clauss, Elizabethtown, Pa.

Refile of abandoned application Serial No. 637,843,
October 14, 1932. This application May 15,
1939, Serial No. 273,813

2 Claims. (Cl. 66—198)

The present application is a refile of abandoned application, Serial No. 637,843, filed October 14, 1932.

This invention relates to knitted fabrics, and particularly to that type known in the art as "non-run" fabric.

Plain knitted fabric, such as used in the manufacture of hosiery, underwear, sweaters, etc., consists of successively formed, horizontally extending rows or courses of stitches each consisting of a series of loops, formed on the needles of the machine producing the fabric, which are connected transversely or coursewise of the fabric by connecting loops, commonly referred to as sinker loops, which lie between the needle loops, the needle loops of one course being interlooped with the corresponding needle loops of the adjacently disposed courses, and the sinker loops of each course being likewise interlooped with the corresponding sinker loops of the adjacently disposed courses, producing in the fabric substantially straight vertical lines of loops known as "needle wales" and "sinker wales" respectively.

Should the thread, of which the fabric is formed, break in one of the needle loops the corresponding needle loop in the preceding course will be released, and it in turn will release the next loop in the next preceding course and so on through the fabric forming what is commonly known as a "runner" that will progress in one direction along the wale in which the broken loop occurs.

Should the thread break in one of the sinker loops the corresponding sinker loops of each of the succeeding courses will be released in a manner similar to the release of the needle loops above referred to, consequently producing a runner which will progress along the sinker wale in which the break occurs in the opposite direction to that produced by the breaking or dropping of a needle loop.

Various attempts have been made to produce a "non-run" fabric wherein a thread breaking in either a needle wale or a sinker wale may produce a runner, but, the runner will be arrested after progressing through but a relatively few number of courses.

One example of the "non-run" type of fabric is disclosed in the United States Letters Patent to Nathan Schwartz No. 1,470,490, dated October 9, 1923, wherein a runner starting in a single wale will be arrested after progressing to a maximum of four courses.

In this particular type of fabric alternate

wise of the fabric from the wale in which the stitch originates to the wale next adjacent thereto, half the stitch being retained in the wale of origin and the other half being interknit with a stitch in the said adjacent wale. This procedure effectively stops runners in either direction when a stitch breaks in one or more of the wales of the fabric. The courses intermediate those in which the stitches are laterally spread are of the plain variety, and the spreading of the stitches is alternated in the adjacently disposed wales.

While fabric of this kind is effective insofar as the "non-run" feature is concerned, the staggered relation of the spreading of the loops throughout the fabric causes the individual wales and courses to be distorted from their regular transverse and vertical right angle relation to each other, producing what in effect is generally known as a "netted" or "mesh" fabric having relatively large openings therein. Insofar as hosiery is concerned, and particularly women's hosiery, "netted" and "mesh" fabrics have lost favor, while fabrics having the appearance of the "plain" fabric, above referred to, are in demand.

The object of the present invention is to produce a "non-run" fabric wherein the construction responsible for the tendency of the fabric to assume the "netted" or "mesh" appearance is changed to one causing the fabric to assume an appearance more closely approaching that of the plain fabric.

The construction and method of producing a "non-run" fabric according to the principles of the present invention will be disclosed herein-after, reference being had to the accompanying drawings, of which:

Fig. 1 is a fragmentary face view diagrammatically illustrating the fabric on an enlarged scale;

Fig. 2 is an enlarged stitch diagram of the reverse or back face of the fabric, as produced according to the principles of the present invention;

Figs. 3 to 10 inclusive are respectively diagrammatic plan views illustrating various steps in producing the fabric according to the principles of the present invention; and

Figs. 11 to 20 respectively are longitudinal sectional elevations further illustrating the various steps in the production of the fabric.

As shown more clearly in Fig. 2, the fabric comprises a plurality of successively knit courses 1, 2, 3, 4, etc. producing needle wales 5, 6, 7, 8, 9 and 10 alternating with sinker wales 11, 12, 13, 14, 15, etc. The odd numbered courses 1, 3, etc. are composed entirely of plain stitches 19, 19, 55

while the even numbered courses 2, 4, etc. are composed of plain stitches 20, alternating with locking stitches 21. Each locking stitch is composed of a plain stitch spread coursewise of the fabric from its wale of origin to the next adjacent wale thereto. For example, in course 4 the locking stitches 21 originate respectively in wales 5, 7, 9, and are spread over and interlocked with the plain stitches 20 in the wales 6, 8, 10, while in course 2 the locking stitches 21 originate respectively in wales 6, 8 and 10 and are spread coursewise and interlocked with the plain stitches 20 of wales 7, 9, etc.

The laterally spread portion of each locking stitch 21 is circularly twisted in line with the course in which the locking stitch is disposed, the twist taking place on a line extending coursewise of the fabric, substantially in the plane of the needles producing the fabric, whereby instead of just a half needle loop being disposed, for example, in the wale 5 and the other half of the loop being disposed in wale 6, reference now being had to course 4, a complete substantially circular locking loop 22 is produced in wale 6 and a complete needle loop or stitch is produced in wale 5, the laterally extended portion of the locking stitch 21, as a result of the half circular twist, crossing upon itself, as indicated at 23, to produce these two complete loops, and being held in this crossed relation by the sinker loop 24 in the sinker wale 11 that is disposed intermediate the needle wales 5 and 6 respectively.

By slackening the tension of the thread or by increasing the length of the stitches when one of the locking courses 2, 4, etc. is being produced a sufficient amount of extra thread is provided to permit the formation of the locking loops 22, and at the same time permit all of the stitches in the said locking courses 2, 4, etc. to be of the same length as the stitches of the intermediate plain courses 1, 3, etc., whereby the needle wales 5, 6, 7, etc. will retain more nearly their true longitudinal parallel alignment, as a result of the reduction in the amount of coursewise tension produced by the lateral spreading of the locking stitches, which otherwise would distort the wales.

In producing the fabric a course of regular plain stitches, such as that illustrated at 1, is first formed on and by the needles 25 in the usual manner (see Fig. 3). While these loops are still held on the needles the thread is laid to and sunk around the needles, in the usual manner, to produce a succeeding course of plain stitches, which are pulled through the stitches of course 1, in the usual manner. While this newly formed course of stitches is held on the needles 25, spreading points 30, similar to the harrowing points of a flat knitting machine, are brought into engagement with alternate needles 25, as illustrated in Figs. 3 and 11, to pass into the stitches 21 and between the said stitches and the needles on which the stitches are hung.

Instead of completely lifting the stitches 21 from the needles 25, the spreading points 30 and the needles 25 rise from the position shown in Fig. 11, where the stitches 21 are resting on top of the knock-over bits 31, to a position where the lower ends of the spreading points 30 are above the plane of the said knock-over bits, the spreading points 30 and needles 25 moving apart and away from each other, in the plane of the needle, until the points 30 are clear of the beards 26 of the needles, as illustrated in Figs. 4 and 12.

While the needles and spreading points are maintained in this same spaced relation, the said

spreading points 30 are shogged laterally out of line with the needles on which the stitches 21 were formed to positions in line with the needles next adjacent to those from which the stitches 21 have been spread and on which the plain 5 stitches 20 of the new course are still hanging, as illustrated in Fig. 5.

While maintained in this new alignment the points 30 and needles 25 move relative to and toward each other in the planes of the needles until 10 the ends 27 of the beards 26 of the needles 25 on which the stitches 20 are hanging are seated in the grooves 32 of the spreading points 30.

With the free ends 27 of the beards 26 of the needles seated in the grooves 32 of the spreading 15 points 30 relative movement between the needles and transfer points in a direction longitudinally of each is effected, whereby the extreme end or point 27 of each needle beard 26 slides downwardly in the groove 32 and assumes a position between the leg 21a of the stitch 21, which is then extending diagonally across and in front of the needle 25, from the spreading point 30 to the stitch of the preceding course in the wale of origin of the stitch 21, the second leg 21b of 25 the stitch 21 extending diagonally from the spreading point 30 to the needle 25 from which the stitch is being spread, and which still retains contact with the one side of the stitch 21, this relation being clearly shown in Fig. 13 of the 30 drawing.

The spreading points 30 and the needles 25 are then moved further toward each other in the plane of the needle from the position shown in Fig. 13 to that shown in Fig. 14 wherein the beard 35 26 of the needle is closed on the leg 21a of the stitch 21 and the plain stitch 20 normally retained by the needle. The spreading points 30 are then raised relative to the needles whereby the portion 21c of the stitch 21 which connects 40 the leg 21a and 21b and passes around the spreading point is slipped off the end of the spreading point and is caught and held by the beard 26 of the needle, as clearly shown in Figs. 7 and 15.

The needles are then lowered to the position shown in Figs. 16 wherein the fabric rests on top of the knock-over bits 31 and in this movement of the needles the portion 21c of the stitch 21 is rolled around and over the top or point of the 50 needle, the leg 21a of the stitch moving from the front to the back of the needle and crossing the leg 21b intermediate the needles, the portion 21c of the stitch 21 then becomes a full loop 22 extending completely around the shank 28 of the 55 needle immediately adjacent the point 29 thereof, as clearly shown in Figs. 8 and 16.

The needles then rise through the plain stitches 20 held thereon and the locking loops 22 held on the alternate needles in superposed relation to the 60 plain stitches 20 thereon, the sinkers 33 now being in their outer position and engaging the said loops and stitches to slide the same down on the needles as the needles rise therethrough, the needles rising relative to the loops and stitches 65 until the said loops and stitches are well below the points 21 of the beards 26 of the needles, and wherein the needles and sinkers are in their usual normal position to receive thread for the next course of stitches to be formed.

The thread is fed to the needles and sinkers in the usual manner by a thread guide such as that illustrated at 34 in Fig. 17. After the sinking of the thread around the needles the needles are lowered and move into engagement with the 75

presser face 35 in the usual manner, closing the beards around the new thread which is then well up on the needle toward the points thereof, the points of the beards being closed above the 5 stitches 20 and loops 22 held on the needles from the preceding course, as clearly shown in Fig. 18.

The new thread is then pulled through the previously formed stitches 20-21 and locking loops 22, in the manner illustrated in Figs. 19 10 and 20, which are then cast from the needles in the usual manner and assume the position shown in Fig. 10 relative to the new course of stitches just completed by the needles and which are hanging on the needles as shown in Fig. 10.

15 The catching of the one leg of the spread locking stitch solely by the beard of the needle and the throwing of the caught portion of the stitch over the point or upper end of the needle as above described twists the spread portions of the 20 stitches 21 substantially along the line x, x, Fig. 10, in or immediately adjacent the plane of the needles 25 and where the sinker loops 24 interlock with the needle loops 20 and 21. The sinker loops press against the twists where the two legs 25 of the stitches 21 cross each other to provide and maintain the complete loops 22.

Throughout the foregoing specification the spreading of the loops and the twisting of the spread loops to effect locking for the prevention 30 of the formation of runners or ladders in the fabric has been described as occurring at the intersections of alternate wales and alternate courses. However, the invention is not restricted to this particular arrangement although such arrangement is preferable. It will be clear that the 35 spreading of loops and the twisting of the spread loops may take place in every third, fourth, or other course, as desired, and in every second, third, or fourth wale, etc., the distribution of the locking loops being so arranged in any instance that a runner will be stopped after ad-

vancing across a relatively few courses and with the locking loops so arranged that runners in each and every wale will be arrested accordingly.

I claim:

1. A non-run knitted fabric comprising alternating tight and loose courses of stitches forming needle wales alternating with sinker wales extending substantially at right angles to said courses, locking stitches at the intersections of alternate needle wales and said loose courses, said 10 locking stitches each being spread laterally from the needle wale of a loose course in which said stitch originates to and interknit with a single stitch of said loose course in the needle wale next adjacent to said wale of origin, said locking 15 stitch being twisted circularly upon itself in line with said loose course and with the sinker wale disposed between said adjacently disposed needle wales.

2. A non-run knitted fabric comprising alternating tight and loose courses of stitches forming needle wales alternating with sinker wales extending substantially at right angles to said courses, locking stitches at the intersections of alternate needle wales and said loose courses, 20 said locking stitches each being spread laterally from the needle wale of a loose course in which said stitch originates to and interknit with a single stitch of said loose course in the needle wale next adjacent to said wale of origin, said 25 locking 30 stitch being twisted circularly upon itself in line with said loose course and with the sinker wale disposed between said adjacently disposed needle wales, said twist occurring at a point where a sinker loop of the next succeeding tight 35 course of said sinker wale is interknit with the stitch at said intersection and the stitch next adjacent thereto upon which the intersection stitch is spread.

GUIDO O. CLAUSS. 40
